UNITED STATES PATENT OFFICE.

HENRY MULLER, OF OAKLAND, CALIFORNIA.

WINDOW-SCREEN HINGE.

1,417,097.

Specification of Letters Patent. Patented May 23, 1922.

Application filed January 25, 1921. Serial No. 439,748.

To all whom it may concern:

Be it known that I, HENRY MULLER, a citizen of the United States, residing at Oakland, in the county of Alameda and State of California, have invented certain new and useful Improvements in Window-Screen Hinges, of which the following is a specification.

My invention is an improved window screen hinge including a pair of interchangeable detachable leaves which may be used on either side of the screen.

Referring to the annexed drawing in which my invention is illustrated and which forms a part of this specification:

Figure 1 is a front view of a screen window with the screen hinged by my hinge to the window frame.

Figure 2 is a vertical section of the window frame taken on line 2—2 of Figure 1.

Figure 3 is a plan view of one of the hinge leaves.

My hinge includes two leaves 1—1, which are identical in construction. Each leaf has a hook 2 at one corner, an offset 3 diagonally opposite said hook, a vertical slot 4 in said offset, a vertical slot 5 about midway between the slot 4 and the hook side of the leaf, and a screw hole 6 below the slot 5.

A leaf 1 is secured to the inside of each side member of the window frame 7 immediately under the upper frame member, with its hook 2 uppermost and projecting outwardly and upwardly from the frame. Said leaves are secured in position by screws 8 and 9 driven respectively through the slots 5 and the holes 6 in said leaves into the side frame members.

A leaf 1 is secured to the front of the frame of the window screen 10 at each upper corner thereof with the offsets 3 uppermost

and extending outwardly from the sides of the window screen and the hooks 2 lowermost and projecting inwardly of the screen. Said leaves are secured in position on the screen by screws 11 and 12 driven through the slots 5 and holes 6 in said leaves.

In placing the screen in position in the window frame the hooks 2 of the leaves secured to the window frame are inserted through the slots 4 in the leaves secured to the screen, whereby the screen is hung in the frame so that it may be swung open or closed from its upper edge, the hooks 2 of the leaves secured to the window frame and the slots 4 of the leaves secured to the screen, forming the fulcrums of the screen hinges.

In securing the hinge leaves in position the screws 8 and 11 are first driven through the slots 5 into the screen and frame and the leaves adjusted so that the hooks 2 of the leaves secured to the window frame register properly with the slots 4 of the leaves secured to the screen. The screws 9 and 12 are then driven through the holes 6 into the frame and screen.

The screen may be removed from the frame by swinging it up into horizontal position and disengaging the slots 4 of the screen leaves from the hooks 2 of the frame leaves.

Having described my invention, I claim:

A hinge including a pair of leaves, a hook extending from one corner of each leaf, an offset on each leaf diagonally opposite the hook of the leaf, the offset of each leaf having a slot to receive the hook from the other leaf, and means for securing the leaves in position.

In testimony whereof I affix my signature. 80

HENRY MULLER.
